(57) **CLAIM**

The ornamental design for a tactical vest, as shown and described.

DESCRIPTION

FIG. 1 is a front perspective view showing the tactical vest of the present disclosure;

FIG. 2 is a rear perspective view thereof;

FIG. 3 is a front view thereof with the side panels fully folded out;

FIG. 4 is a rear view thereof with the side panels fully folded out;

FIG. 5 is a top plan view thereof shown on a reduced scale, in a flat open condition;

FIG. 6 is a bottom plan view thereof shown on a reduced scale, in a flat open condition of FIG. 1;

FIG. 7 is a left side view of the tactical vest shown in FIG. 1;

FIG. 8 is a right side view of the tactical vest shown in FIG. 1;

FIG. 9 is a front view of FIG. 1 showing a flap of the tactical vest folded up wherein the extend arm fold into and the flap folds over;

FIG. 10 is a left side view of FIG. 9; and,

FIG. 11 is a right side view of FIG. 9.

The broken lines shown in the drawings illustrate unclaimed features and form no part of the claimed design.
